CLAIM

The ornamental design for a laser cutting machine, as shown and described.

DESCRIPTION

1. Laser cutting machine

1.1 : Front

1.2 : Right perspective view

1.3 : Left perspective view

1.4 : Top perspective view

1.5 : Left

1.6 : Right

1.7 : Back

The present design corresponds to a laser cutting machine:

1.1 front view, 1.2 perspective view from right side, 1.3 perspective view from left side, 1.4 perspective view from top, 1.5 left side view, 1.6 right side view, 1.7 back view. The broken lines represent portions of the laser cutting machine that form no part of the claimed design.

1 Claim, 7 Drawing Sheets
